FOREIGN PATENT DOCUMENTS

JP 3294043 5/2002

Primary Examiner—Jack W. Lavinder

(57) **ABSTRACT**

A pouch has an airtight elongate closure mechanism adapted to provide vacuum retention within an interior of the pouch over an extended period of time when sealed. The closure mechanism includes a first pair of interlocking members that resealably mate together, a second pair of interlocking members that resealably mate together, and sealing members that form an air tight seal disposed between the first and second pairs of interlocking members. The closure elements may be connected with opposing sidewalls of the pouch in a manner designed to provide differential opening and closing forces. The pouch may also include a check valve and air evacuation channels to aid in evacuating air from the interior.

BACKGROUND OF THE INVENTION**1. Field of the Invention**

The present invention relates generally to a resealable closure mechanism such as may be used on a thermoplastic pouch.

2. Description of the Background of the Invention

Thermoplastic pouches having one or more resealable closure mechanisms extending along an opening into an interior thereof are often used to store perishable contents, such as food. In order to keep the food stored inside the pouch fresh for an extended period, a user may press excess air out of the pouch before completely sealing the closure mechanism. Other pouches have been developed that have a separate air evacuation route so that air may be removed from the pouch after the closure mechanism has already been sealed. Some such pouches allow a vacuum to be formed inside the pouch before the pouch is sealed so as to vacuum pack the contents of the pouch.

Special resealable closure mechanisms have been used in an attempt to maintain the vacuum in the pouch over extended periods of time. Those closure mechanisms have two opposing closure elements that form an interlocking section and a sealing section in an attempt to form an airtight seal. For example, in some such closure mechanisms, one closure element has a sealing member spaced between two in-turned hooks and the other closure element has a channel defined by and between two out-turned hooks. The sealing member abuts against inside surfaces of the out-turned hooks to form a seal therewith.

In other closure mechanisms, each closure element has a sealing member disposed between two interlocking members. The sealing members press against each other when the interlocking members are appropriately interlocked to form the seal. In one closure mechanism, for example, one closure element has two spaced out-turned male hooks that interlock with two complementary in-turned female hooks. A pressing rib spaced between the out-turned male hooks is wedged into a tapered channel defined by two tightening walls spaced between the in-turned female hooks. Each tightening wall also presses against an inner surface of the adjacent out-turned male hook.

In another closure mechanism, one closure element has two interlocking bulbous members spaced between two asymmetrical arrow-shaped members projecting from one base. The other closure element has three interlocking bul-

2

bous members spaced between two interlocking groove elements projecting from another base. The closure elements resealably mate with each asymmetrical arrow-shaped member interlocked with the opposing groove element and the two interlocking bulbous members on the one closure element engaged in a tight interfering fit between successive ones of the interlocking bulbous members on the other closure element. One of the closure elements has a backing member that may be attached directly to a pouch wall, and the other closure element has a backing member that is attached at only one end to another flange element that may be attached directly to a pouch wall.

SUMMARY OF THE INVENTION

According to one aspect of the invention, an airtight resealable closure mechanism having an elongate substantially constant profile extending between a first end and a second end includes a first closure element and a second closure element. The first closure element includes a first interlocking member, a second interlocking member, and a first sealing member, each protruding from a first base member, wherein the first sealing member is disposed between the first and second interlocking members. The second closure element includes a third interlocking member, a fourth interlocking member, and a second sealing member, each protruding from a second base member, wherein the second sealing member forms a tapered channel and is disposed between the third and fourth interlocking members. The first and second interlocking members are resealably interlocked with the third and fourth interlocking members, respectively. Each of the first and second interlocking members comprises a pair of arms forming a channel-shaped female interlocking member, and each of the third and fourth interlocking members comprises an arrow-shaped male interlocking member. The first sealing member is wedged into the tapered channel of the second sealing member, whereby an airtight seal is formed. The first and second sealing members are spaced from each of the first, second, third, and fourth, interlocking members.

According to another aspect of the invention, an airtight resealable closure mechanism having an elongate substantially constant profile extending between a first end and a second end includes a first closure element and a second closure element. The first closure element includes a first interlocking member, a second interlocking member, and a first rib having a bulbous head, each protruding from a first base member, wherein the first rib is disposed between the first and second interlocking members. The second closure element includes a third interlocking member, a fourth interlocking member, and a first wall spaced from a second wall to define a channel therebetween, each protruding from a second base member, wherein the channel has substantially parallel sides and is disposed between the third and fourth interlocking members. The first and second interlocking members are resealably interlocked with the third and fourth interlocking members, respectively. Each of the second and third interlocking members comprises a pair of arms forming a channel-shaped female interlocking member, and each of the first and fourth interlocking members comprises an arrow-shaped male interlocking member. The first rib is wedged into the channel, whereby an airtight seal is formed. The first rib, the first wall, and the second wall are spaced from each of the first, second, third, and fourth, interlocking members.

According to yet another aspect of the present invention, an airtight resealable closure mechanism having an elongate substantially constant profile extending between a first end and a second end includes a first closure element and a second

closure element. The first closure element includes a rib disposed between a first arrow-shaped male interlocking member and a second arrow-shaped male interlocking member, each of the first and second interlocking members and the rib protruding from one side of a first base member. The second closure element includes first and second walls disposed between a third arrow-shaped male interlocking member and a fourth arrow-shaped male interlocking member, each of the third and fourth interlocking members and the first and second walls protruding from one side of a second base member. The first interlocking member is resealably interlocked with the third interlocking member and the second interlocking member is resealably interlocked with the fourth interlocking member. The rib is wedged against the first and second walls, whereby an airtight seal is formed between the rib and the first and second walls.

BRIEF DESCRIPTION OF THE DRAWINGS

FIG. 1 is an isometric view of a pouch and an airtight closure mechanism according to one aspect of the present invention;

FIG. 2 is a partial cross-sectional view along the line 2-2 of FIG. 1 with portions behind the plane of the cross-section omitted for clarity;

FIG. 3 is a partial cross-sectional view similar to the view of FIG. 2 of an airtight resealable closure mechanism according to another embodiment;

FIG. 4 is a partial cross-sectional view similar to the view of FIG. 2 of an airtight resealable closure mechanism according to still another embodiment;

FIG. 5 is a partial cross-sectional view similar to the view of FIG. 2 of an airtight resealable closure mechanism of yet another embodiment;

FIG. 6 is a partial cross-sectional view similar to the view of FIG. 2 of an airtight resealable closure mechanism according to a further embodiment; and

FIG. 7 is a partial cross-sectional view similar to the view of FIG. 2 of an airtight resealable closure mechanism of a still further embodiment.

Other aspects and advantages of the present invention will become apparent upon consideration of the following detailed description, wherein similar structures have the same reference numerals throughout.

DETAILED DESCRIPTION

As seen in FIGS. 1 and 2, a resealable pouch 10 includes a first sidewall 12 and a second sidewall 14 that are connected, such as by folding, heat seal, and/or adhesive, along three peripheral edges 20a, 20b, and 20c to define a sealable interior space 16 therebetween, and an opening 18 is defined along a top edge 20 where the first and second sidewalls are not connected so as to allow access to the interior space. A resealable elongate closure mechanism 22 extends along the first and second sidewalls 12, 14 near the opening 18 between the peripheral edge 20a and the peripheral edge 20c of the pouch 10 to allow the opening to be repeatedly sealed and unsealed, thereby closing and opening, respectively, the opening.

When occluded, the closure mechanism 22 provides an air-tight seal such that a vacuum may be maintained in the pouch interior 16 for a desired period of time, such as days, months, or years, when the closure mechanism is sealed fully across the opening 18. In one embodiment, the pouch 10 may include a second opening 18a through one of the sidewalls 12, 14 covered by a valve 28, such as a check or one-way valve,

to allow air to be evacuated from the pouch interior 16 and maintain a vacuum when the closure mechanism 22 has been sealed. As shown in FIG. 1, the valve 28 may be disposed on the first sidewall 12 spaced from the closure mechanism 22.

5 The valve 28 provides a fluid path with fluid communication between the pouch interior 16 and an exterior 118 of the pouch. Illustrative valves useful in the present invention include those disclosed in, for example, Newrones et al. U.S. Patent application publication No. 2006/0228057. Other 10 valves useful in the present invention include those disclosed in, for example, Ser. Nos. 11/818,592, 11/818/586 and 11/818,591, each filed on the same day as the present application.

Although not shown, in some embodiments an evacuation 15 pump or device may be used to evacuate fluid from the pouch 10 through, for example, the valve 28 disposed in one of the sidewalls 12, 14, or in or through the closure mechanism 22 or in one of the peripheral edges 20a-20c of the pouch. Illustrative evacuation pumps or devices useful in the present invention include those disclosed in, for example, Ser. No. 11/818, 703, filed on the same day as the present application.

The pouch 10 may include relief on or along an interior 20 surface of one or both of the first and second sidewalls 12, 14 to provide air flow channels 30 between the sidewalls when a 25 vacuum is being drawn through the check valve 28. In this manner, the pouch 10 provides a complete evacuable system within which food, for example, may be stored in a reusable vacuum pouch. One or both sidewalls, such as the second sidewall 14, may also be embossed or otherwise textured with 30 a pattern, such as a diamond pattern, on one or both surfaces spaced between the bottom edge 20b and the closure mechanism 22 and including a smooth area adjacent the bottom edge and the top edge 20, or a separate textured and embossed patterned wall may be used to provide additional flow channels (not shown) within the pouch interior 16. Illustrative flow channels useful in the present invention include those disclosed in Zimmerman et al. U.S. Patent Application Publication No. 2005/0286808 and Tilman et al. U.S. Patent Application Publication No 2006/0048483. Other flow channels 35 useful in the present invention include those disclosed in, for 40 example, Ser. No. 11/818,584, filed on the same day as the present application.

As seen in FIG. 2, the closure mechanism 22 includes an interlocking closure element 32 that releasably interlocks and 45 seals with an opposing interlocking closure element 34. Each interlocking closure element 32, 34 has a substantially constant elongate cross-sectional profile that extends longitudinally between the peripheral edge 20c and the peripheral edge 20a of the pouch 10 to form a continuous seal therealong 50 when fully interlocked with the opposing closure element. In one embodiment, closure element 32 is disposed along the first sidewall 12 and the closure element 34 is disposed along the second sidewall 14 opposite the first closure element so as to 55 resealably interlock along an entire length thereof.

The interlocking closure element 34 has an elongate closure profile including a sealing section spaced between two interlocking members 36, 38, each projecting from a common side of a base member 40. In one embodiment, the interlocking member 36 has an arrow-shaped male interlocking profile, and the interlocking member 38 has a channel-shaped 60 female interlocking profile. The arrow-shaped male interlocking profile 36 includes a shaft extending outwardly from the base member 40 and a symmetrical head with barbs extending from opposite sides of a distal end of the shaft spaced from the base member. The channel-shaped female interlocking profile 38 includes two spaced arms extending 65 from the backing member 40, each arm having an in-turned

hook at a distal end thereof, to form a channel therebetween. The sealing section of the closure element 34 includes a sealing wall 42 and a sealing wall 44 spaced apart and projecting outwardly from the base member 40. The sealing walls 42, 44 in one embodiment are tapered, having a tip that is narrower than a base, thereby forming a tapered generally V-shaped channel 46 therebetween. In one embodiment, the sealing walls 42, 44 and the male and female interlocking profiles 36, 38 are all approximately the same height from the base member 40.

The interlocking closure element 32 has an elongate second closure profile including a sealing section spaced between two interlocking members 48, 50, each projecting from a common side of a backing member 52. In one embodiment, the interlocking member 48 has a channel-shaped female interlocking profile, and the interlocking member 50 has an arrow-shaped male profile, complementary with the respective male and female interlocking profiles 36, 38, respectively, of the closure element 34. The sealing section of the closure element 32 includes at least one sealing rib that wedges into the tapered channel 46 between the opposing sealing walls 42, 44. In one embodiment, the sealing section includes a first sealing rib 54 disposed between a second sealing rib 56 and a third sealing rib 58. Each sealing rib 54, 56, 58 has a bulbous head 60, such as a cross member, spaced from the base 52 proximate a distal end of a wall 62, which projects from the base 52. In one embodiment, each sealing rib 54, 56, 58 has a T-shaped cross-section. In other embodiments, the bulbous head 60 may have other shapes that project laterally from the wall 62, such as rounded, asymmetrical, slanted, or multiple projections, for example. The first and second interlocking closure elements 32, 34 may include closure profiles as described previously herein. However, the configuration and geometry of the closure elements 32, 34 and closure profiles as disclosed herein may vary.

In a further embodiment, one or both of the closure elements 32, 34 may include one or more textured portions, such as a bump or crosswise groove in one or more of the interlocking members 36, 38, 48, 50 in order to provide a tactile sensation, such as a series of clicks, as a user draws the fingers along the closure mechanism to seal the closure elements across the opening 18. In another embodiment, all of the interlocking members 36, 38, 48, 50 include textured portions along the length of the profile to provide tactile and/or audible sensations when closing the closure mechanism 22. Further, in some embodiments, a sealing material such as a polyolefin material or a caulking composition such as silicone grease may be disposed on or in the closure profiles or closure elements 32, 34 to fill in any gaps or spaces therein when occluded. The ends of the closure profiles or closure elements 32, 34 may also be welded or sealed by ultrasonic vibrations as is known in the art. Illustrative interlocking profiles, closure elements, sealing materials, tactile or audible closure elements, and/or end seals useful in the present invention include those disclosed in, for example, Pawloski U.S. Pat. No. 4,927,474, Dais et al. U.S. Pat. Nos. 5,070,584, 5,478, 228, and 6,021,557, Tomic et al. U.S. Pat. No. 5,655,273, Sprehe U.S. Pat. No. 6,954,969, Kasai et al. U.S. Pat. No. 5,689,866, Ausnit U.S. Pat. No. 6,185,796, Wright et al. U.S. Pat. No. 7,041,249, Pawloski et al. U.S. Pat. No. 7,137,736, Anderson U.S. Patent Application Publication No. 2004/0091179, Pawloski U.S. Patent Application Publication No. 2004/0234172, Tilman et al. U.S. Patent Application Publication No. 2006/0048483, and Anzini et al. U.S. Patent Application Publication Nos. 2006/0093242 and 2006/0111226. Other interlocking profiles and closure elements useful in the present invention include those disclosed in, for example,

U.S. patent application Ser. No. 11/725,120, filed Mar. 16, 2007, and Ser. Nos. 11/818,585 and 11/818,586, each filed on the same day as the present application. It is further appreciated that the closure profiles or closure elements disclosed herein may be operated by hand, or a slider (not shown) may be used to assist in occluding and de-occluding the closure profiles and closure elements.

In a sealed state, the male interlocking profile 50 is interlocked with the female interlocking profile 38, and the female interlocking profile 48 is interlocked with the male interlocking profile 36. The bulbous head 60 of the sealing rib 54 is wedged tightly into the tapered channel 46 against the sealing walls 42, 44. The sealing wall 42 is wedged tightly between and against the bulbous heads 60 of the sealing rib 54 and the sealing rib 56, and the sealing wall 44 is wedged tightly between and against the bulbous heads 60 of the sealing rib 54 and the sealing rib 58. Preferably, the geometry of the sealing walls 42, 44 and the sealing ribs 54, 56, 58 is such that, when the interlocking profiles 36, 38, 48, 50 are occluded together in the sealed state, the distal ends of the sealing walls are spaced from the backing member 52 and the bulbous heads 60 are spaced from the backing member 40, thereby ensuring four air tight seals across the closure elements 32, 34 between the interlocking profiles 36, 48 and 38, 50. Further, the sealing sections are spaced from each interlocking member 36, 38, 48, 50, which provides a sealing section that forms an air tight seal independently of the interlocking members. Of course, more or fewer sealing walls and sealing ribs may be used in other embodiments to form more or fewer air tight seals across the closure elements.

In order to develop differential opening and closing forces, one of the closure elements may be secured continuously to the respective sidewall along the entire profile of the base member, and the other closure element may be secured partially to the respective sidewall along only a portion of the profile. For example, in one embodiment, the closure element 34 is connected with the second sidewall 14 continuously between the interlocking member 36 and the interlocking member 38. The closure element 32 is connected with the first sidewall 12 continuously between the interlocking member 48 and an interior side of the sealing rib 58, and an interior end of the closure element 32 is unconnected with the first sidewall 12 between the interior end of the base 52 and the interior side of the sealing rib 58. In this manner, differential opening and closing forces may be developed because the interior end and interlocking profile 50 of the base 52 of at least the closure element 32 is allowed to hinge away from the first sidewall 12, thereby minimizing an opening force caused by the contents pushing outwardly against the first and second sidewalls 12, 14. In other embodiments, the interior end of either or both closure elements 32, 34 may be unconnected with the respective sidewall 12 or 14, or the interior end of both closure elements may be connected with the respective sidewall.

The closure elements 32, 34 may be connected with the respective first and second sidewalls 12, 14 by many means, such as with adhesives or heat or ultrasonic welding. In one embodiment, the closure elements 32, 34 are connected with the respective sidewalls 12, 14 using an intermediate layer 64 of connecting material, such as thermoplastic weld material, disposed between and connecting the base member 40, 52 of the closure element with the respective sidewall 14, 12. In this embodiment, a hot layer of thermoplastic weld material 64 applied between each closure element 32, 34 and the respective sidewall 12, 14 melts and attaches to both the sidewall and the base member, thereby forming a thermoplastic weld

therebetween, which in some embodiments may provide a good continuous air tight seal between each sidewall and the respective closure element.

In one embodiment, the top edge 20 of one or both of the first and second sidewalls extends upwardly beyond an exterior end of the respective closure element 32, 34. One or more protuberances, for example, grip ridges 66, project from an interior side of one both of the sidewalls 12, 14 between the top edge 20 and the respective closure element 32, 34 to provide additional finger traction in a convenient area for a user to grip for opening the closure mechanism 22.

In one embodiment, the first and second sidewalls 12, 14 and/or the closure mechanism 22 are formed from thermoplastic resins by known extrusion methods. For example, the sidewalls 12, 14 may be independently extruded of thermoplastic material as a single continuous or multi-ply web, and the closure mechanism 22 may be extruded of the same or different thermoplastic material(s) separately as continuous lengths or strands. Illustrative thermoplastic materials include polypropylene (PP), polyethylene (PE), metallocene-polyethylene (mPE), low density polyethylene (LDPE), linear low density polyethylene (LLDPE), ultra low density polyethylene (ULDPE), biaxially-oriented polyethylene terephthalate (BPET), high density polyethylene (HDPE), polyethylene terephthalate (PET), among other polyolefin plastomers and combinations and blends thereof. Further, inner surfaces of the respective sidewalls 12, 14 or a portion or area thereof may, for example, be composed of a polyolefin elastomer such as an AFFINITY™ resin manufactured by Dow Plastics. Such portions or areas include, for example, the area of one or both of the sidewalls 12, 14 proximate and parallel to the closure mechanism 22 to provide an additional cohesive seal between the sidewalls when the pouch 10 is evacuated of fluid. One or more of the sidewalls 12, 14 in other embodiments may also be formed of air-impermeable film. An example of an air-impermeable film includes a film having one or more barrier layers, such as an ethylene-vinyl alcohol copolymer (EVOH) ply or a nylon ply, disposed between or on one or more of the plies of the sidewalls 12, 14. The barrier layer may be, for example, adhesively secured between the PP and/or LDPE plies to provide a multilayer film. Other additives such as colorants, slip agents, and anti-oxidants, including for example talc, oleamide or hydroxyl hydrocinnamate may also be added as desired. In another embodiment, the closure mechanism 22 may be extruded primarily of molten PE with various amounts of slip component, colorant, and talc additives in a separate process. The fully formed closure mechanism 22 may be attached to the pouch body using a strip of molten thermoplastic weld material, or by an adhesive known by those skilled in the art, for example. Other thermoplastic resins and air-impermeable films useful in the present invention include those disclosed in, for example, Tilman et al. U.S. Patent application publication No 2006/0048483.

The fully formed closure elements 32, 34 may be attached along opposite edges of one side of the web by placing or extruding a strip of molten thermoplastic weld material 64 onto the web along or adjacent to each edge of the web and immediately placing a closure element 32, 34 onto each strip of molten thermoplastic weld material. The thermoplastic weld material 64 may then be allowed to cool, the web folded together between the opposite edges to place the closure elements 32, 34 in opposing resealable relation, and the web severed transverse to the web direction into discrete pouches, in a manner well known in the art, to form the pouch 10. According to another embodiment, the web, intermediate layer of connecting material 64, and the closure elements 32,

34 may be extruded together simultaneously, and subsequently cooled, folded, and cut. If used, the check valve 28 may be formed on and/or attached to the web prior to folding or after folding.

5 The resealable pouch described herein can be made by various techniques known to those skilled in the art including those described in, for example, Geiger, et al., U.S. Pat. No. 4,755,248. Other useful techniques to make a resealable pouch include those described in, for example, Zieke et al., 10 U.S. Pat. No. 4,741,789. Additional techniques to make a resealable pouch include those described in, for example, Porchia et al., U.S. Pat. No. 5,012,561. Additional examples of making a resealable pouch as described herein include, for example, a cast post applied process, a cast integral process, 15 and/or a blown process.

Of course, various details shown in FIGS. 1 and 2 may be modified within the spirit of the present invention. For example, the specific orientation of the closure elements 32, 34 with respect to the interior 16 may be altered from the 20 orientation shown in the drawings, such that, for example, the male interlocking profile 36 and the female interlocking profile 48 may be disposed on the interior side 16 of the sealing sections. In addition, the location and/or use of the check valve 28 and the air flow channels 30 may be modified as 25 desired.

Referring to FIG. 3, another embodiment of an airtight closure mechanism 122 includes closure elements 132 and 134, which are similar to the closure elements 32, 34, but with the following differences. The closure element 132 includes 30 the sealing ribs 54, 56, 58 spaced between the interlocking members 38 and 48 projecting from the interior side of the base member 52. Further, the closure element 134 includes the sealing walls 42, 44 spaced between the interlocking members 36 and 50 projecting from the interior side of the 35 base member 40. Spacing the sealing sections comprising the ribs 54, 56, 58 and the walls 42, 44 from the interlocking members 36, 38, 48, 50 may generally provide a high integrity seal that is independent of the interlocking sections. Each 40 interlocking member 36, 50 has an arrow-shaped male interlocking profile, and each interlocking member 38, 48 has a channel-shaped female profile including a pair of arms 70, 72 that interlockingly engage the opposing interlocking member 36 or 50. Disposing both of the interlocking members having a female profile 38, 48 on a common closure element, for 45 example, 132, and disposing both of the male interlocking members 36, 50 on an opposing common closure element, for example, 134, may generally contribute to ease of manufacture of the closure elements.

Each closure element 132 and 134 is attached by an intermediate layer 64 to the respective first or second sidewall 12 or 14 so as to create differential opening force in a similar manner as described previously herein. For example, the closure element 132 is fully attached to the second sidewall 14 with the intermediate layer 64 extending completely between 50 the interlocking members 38 and 48, whereas the closure element 134 is only partially attached to the first sidewall 12 such that the interlocking member 50 and the sealing rib 58 may deflect away from the first sidewall and the interlocking member 36 and sealing ribs 54 and 56 are not able to deflect 55 away from the first sidewall. The remaining features of the closure mechanism 122 are substantially similar to the closure mechanism 22 as previously described herein. In another embodiment, the closure element 132 may be attached to the first sidewall 12 and the closure element 134 may be attached to the second sidewall 14.

Referring now to FIG. 4, a further embodiment of an airtight closure mechanism 222 includes closure elements 232

and 234, which are similar to the closure elements 132 and 134, respectively, but with the following differences. The closure element 232 includes sealing ribs 54, 56, 58 spaced between interlocking members 36 and 38 projecting from the interior side of the base member 52. Further, the closure element 234 includes sealing walls 42, 44 spaced between interlocking members 48 and 50 projecting from the interior side of the base member 40. The bulbous heads 60 on the sealing ribs 54, 56, 58 are arrow-shaped. The sealing walls 42, 44 have substantially parallel facing inner surfaces 74, 76, respectively, thereby defining an un-tapered channel 246 therebetween. The arrow-shaped bulbous heads 60 of the sealing ribs 54, 56, 58 may generally provide a high integrity seal requiring a smaller closing force to engage than the T-shaped bulbous heads of the embodiments described previously herein. Each closure element 232, 234 is attached to the respective first or second sidewall 12, 14 by an intermediate layer 64 so as to create a differential opening force in a similar manner as previously described herein. All other features of the closure mechanism 222 are substantially similar to the closure mechanism 122 as previously described herein. In another embodiment, the closure element 232 may be attached to the second sidewall 14 and the closure element 234 may be attached to the first sidewall 12.

Referring now to FIG. 5, yet another embodiment of an airtight closure mechanism 322 includes closure elements 332 and 334, which are similar to the closure elements 232 and 234, respectively, but with the following differences. The closure element 334 includes sealing walls 342, 344 spaced between the interlocking members 48 and 50 projecting from the interior side of the base member 40. Each sealing wall 342, 344 has a bulbous head 78 spaced from the base member 40 proximate a distal end of a wall 80, which projects from the base 40. In one embodiment, the wall 80 has substantially parallel sides and the bulbous head 78 is generally arrow-shaped. In other embodiments, the walls 80 may be tapered and the bulbous heads 78 may have other shapes that project laterally from the wall 80, such as rounded, asymmetrical, slanted, or having multiple projections. The sealing walls 342, 344 define a channel 346 therebetween, wherein the channel 346 may be tapered or may have substantially parallel opposing side surfaces 374, 376. The addition of the bulbous heads 78 to the sealing walls 342, 344 may generally enhance the likelihood of a high integrity seal when engaged with the arrow-shaped bulbous heads 60 of the sealing ribs 54, 56, 58. The bulbous heads 78 may also provide an additional interlock between the closure elements 332, 334 to supplement the interlocking strength of the interlocking members 36, 38, 48, 50. Each closure element 332, 334 is attached to the respective first or second sidewall 12, 14 by an intermediate layer 64 so as to create a differential opening force in a similar manner as previously described herein. All other features of the closure mechanism 322 are substantially similar to the closure mechanism 222 as previously described herein. In another embodiment, the closure element 332 may be attached to the second sidewall 14 and the closure element 334 may be attached to the first sidewall 12.

Referring now to FIG. 6, a still further embodiment of an airtight closure mechanism 422 includes closure elements 432 and 434, which are similar to the closure elements 332 and 334, respectively, but with the following differences. The sealing sections of the closure elements 432 and 434 are immediately adjacent the interlocking sections. The closure element 434 includes the sealing walls 342, 344 disposed between interlocking members 82 and 84 projecting from the interior side of the base member 40. Further, the closure element 432 includes the sealing rib 54 disposed between

interlocking members 86 and 88 projecting from the interior side of the base member 52. Each of the interlocking members 82, 84, 86, 88 has a male interlocking profile, which in one embodiment includes two barbs projecting from opposite sides of a shaft forming an arrow shape. The interlocking member 82 interlocks with the interlocking member 86, and the interlocking member 84 interlocks with the interlocking member 88. A barb 90 extending from a side facing the sealing section of a distal end of the shaft of each male interlocking member 82, 84 engages and interlocks with a barb 92 extending from a side facing away from the sealing section of a distal end of the shaft of each corresponding male interlocking profile member 86, 88. Further, a barb 94 extending from a side facing the sealing section of the distal end of the shaft of each male interlocking member 86, 88 makes contact with each sealing wall 342, 344, respectively. Providing this embodiment with all male interlocking members 82, 84, 86, 88 may generally provide for ease of manufacture by requiring extrusion of only male profiles. Further, disposing the interlocking members 82, 84, 86, 88 immediately adjacent to the sealing sections of the closure elements 432 and 434 may provide a closure mechanism 422 that is more rigid overall and thereby less resistant to deformation.

Each closure element 432, 434 is attached to the respective first or second sidewall 12, 14 by an intermediate layer 64 so as to create a differential opening force in a similar manner as previously described herein. For example, the intermediate layer 64 extends behind all the interlocking members 82, 84 and sealing walls 342, 344 on the closure element 434, and the intermediate layer extends behind only the sealing rib 54, the interlocking member 86, and an upper portion of the base member 52 on the closure element 432. Other portions of the closure mechanism 422 shown in FIG. 6 are substantially similar to the corresponding portions of the closure mechanism 322 as previously described herein. In another embodiment, the closure element 432 may be attached to the second sidewall 14 and the closure element 434 may be attached to the first sidewall 12.

Referring now to FIG. 7, yet a further embodiment of an airtight closure mechanism 522 includes closure elements 532 and 534, which are similar to the closure elements 432 and 434, respectively, but with the following differences. The closure element 534 includes sealing walls 542, 544 disposed between the interlocking members 82 and 84 projecting from the interior side of the base member 40. In one embodiment, the sealing walls 542, 544 have substantially parallel opposing sides that define an un-tapered channel 546 therebetween, similar to the same features in the embodiment of FIG. 4. In another embodiment, the sealing walls 542, 544 have tapered opposing sides that define a tapered channel 546 therebetween, which is narrower near the base 40 and wider at a distal end of the sealing walls. The barb 94 extending from the side facing the sealing section of the distal end of the shaft of each male interlocking member 86, 88 contacts each sealing wall 542, 544, respectively. In one embodiment, the side of each sealing wall 542, 544 is tapered toward the distal end, which causes the sealing wall to wedge against the respective barb 94 when the closure elements 532, 534 are interlocked together. Disposing the interlocking members 86, 88 so that occlusion of the closure mechanism 522 forces the interlocking members 86 and 88 inwardly against walls 542 and 544, respectively, may provide a closure mechanism 522 having a high integrity seal that is more rigid overall compared to embodiments having sealing sections spaced from interlocking sections.

Each closure element 532, 534 is attached to the respective first or second sidewall 12, 14 by an intermediate layer 64 so

11

as to create a differential opening force in a similar manner as previously described herein. Other portions of the closure mechanism **522** are substantially similar to the corresponding portions of the closure mechanism **422** as previously described herein. In another embodiment, the closure element **532** may be attached to the second sidewall **14** and the closure element **534** may be attached to the first sidewall **12**.

In further embodiments, more or fewer sealing walls and sealing ribs may be used in each embodiment described herein in order to form more or fewer air tight seals across the closure elements. Although various specific embodiments have been shown and described herein, this specification explicitly includes all possible permutations of combinations of the features, structures, and components of all the embodiments shown and described.

INDUSTRIAL APPLICABILITY

An airtight resealable closure mechanism for a pouch is presented that may be used to pack and store perishable items contained therein in an air-free or vacuum environment. The closure mechanism includes a sealing section that may be separate from an interlocking section and may therefore provide a more secure air tight seal. Clearly, many other and varied uses of the pouch and closure mechanism disclosed herein are also possible.

Numerous modifications to the present invention will be apparent to those skilled in the art in view of the foregoing description. Accordingly, this description is to be construed as illustrative only and is presented for the purpose of enabling those skilled in the art to make and use the invention and to teach the best mode of carrying out same. The exclusive rights to all modifications which come within the scope of the appended claims are reserved. All patents, patent publications and applications, and other references cited herein are incorporated by reference herein in their entirety.

We claim:

1. An airtight resealable closure mechanism having an elongate substantially constant profile extending between a first end and a second end, the profile comprising:
  - a first closure element having a first interlocking member, a second interlocking member, and a first sealing member, each protruding from a first base member, wherein the first sealing member is disposed between the first and second interlocking members; and
  - a second closure element having a third interlocking member, a fourth interlocking member, and a second sealing

12

member, each protruding from a second base member, wherein the second sealing member forms a generally V-shaped tapered channel and is disposed between the third and fourth interlocking members;

5 wherein the first interlocking member is resealably interlocked with the third interlocking member and the second interlocking member is resealably interlocked with the fourth interlocking member;

10 wherein each of the first and second interlocking members comprises a pair of arms forming a channel-shaped female interlocking member, and wherein each of the third and fourth interlocking members comprises an arrow-shaped male interlocking member;

15 wherein the first sealing member is wedged into the generally V-shaped tapered channel of the second sealing member, whereby an airtight seal is formed; and

wherein the first and second sealing members are spaced from each of the first, second, third, and fourth, interlocking members.

20 2. The closure mechanism of claim 1, wherein the first sealing member comprises a first rib disposed between a second rib and a third rib, wherein each of the first, second, and third ribs is T-shaped, and wherein the first rib is wedged within the generally V-shaped tapered channel.

25 3. The closure mechanism of claim 2, wherein the second sealing member comprises a first wall spaced from a second wall defining the generally V-shaped tapered channel therebetween, wherein the first wall is disposed between the first rib and the second rib, and the second wall is disposed between the first rib and the third rib.

30 4. The closure mechanism of claim 3, wherein the first wall is wedged between the first and second ribs and the second wall is wedged between the first and third ribs.

35 5. The closure mechanism of claim 1, wherein the first closure element is continuously connected to a first sidewall between the first interlocking member and the second interlocking member, and wherein the second closure element is continuously connected to a second sidewall between the third interlocking member and the second sealing member and not connected to the second sidewall proximate the fourth interlocking member, and one or more of the first, second, third, and fourth interlocking members includes a textured portion along the length of each member to provide tactile and/or audible sensations when the closure mechanism is 40 45 occluded.
